INVENTOR
EDWARD C. COOLEY

By *Albert C. Bell*
ATTORNEY.

UNITED STATES PATENT OFFICE.

EDWARD C. COOLEY, OF ELGIN, ILLINOIS.

VALVE TOOL.

Application filed May 13, 1925. Serial No. 29,865.

My invention relates to an improved construction of valve tool for repairing valves of the kind ordinarily employed with pneumatic tires used for bicycles, automobiles and other purposes. By my invention I provide a tool adapted to perform all of the operations required in repairing valves of the kind referred to, by making the tool in several parts that will screw together in desired arrangements, these parts being made so that when the parts are all screwed together, they form a straight cylindrical tool of a size that may be conveniently held in the hand of the user and conveniently carried in the pocket, the complete tool being of relatively small diameter and without projecting parts of any kind that interfere with the ready use of the tool or that could injure the hands of the user.

More specifically, I provide on the several parts of the tool a die for cleaning the threads on the outer surface of a valve stem, a tap for cleaning the threads on the inner surface of the valve stem, a socket wrench for removing the valve core from the stem, and a tapered threaded member for removing the small valve sleeve and wire of the valve core from the stem in case the parts of the valve core become jammed in the valve stem. I am aware that various devices have been proposed heretofore for accomplishing these results, but as far as I am aware none of these earlier constructions have been made in a manner equivalent to the construction of the present device, nor have they as far as I am aware, the superior advantages of my present device. By my construction, the socket wrench arrangement is provided with an external tubular guide loosely fitting the outer surface of the valve stem, which I find is a material aid in centering the tool on the stem and holding it in axial alinement with the stem while engagement is being effected between the wrench portion and the projecting keys on the valve sleeve within the stem, this relation also serving to retain the parts in engagement during the removing operation so that a proper engagement is had at all times between the slots in the wrench and the keys projecting from the valve sleeve. This further results in the possibility of conveniently and positively locating the wrench on the valve stem, even though the illumination of the valve stem is so poor that it cannot be distinctly seen. On account of the central wire of the valve core projecting slightly from the valve stem, where it is necessary to enter the wrench portion of similar devices heretofore used, into the valve stem without any guiding devices, correct location of the wrench in the stem is difficult, particularly where the valve stem is not well enough lighted to be clearly seen. With my improved construction all that is required is to locate the tubular guide on the end of the valve stem, this relation being conveniently effected even if the stem cannot be seen, after which the wrench portion will effect proper engagement with the sleeve of the valve core without further care on the part of the operator. A further important feature of my construction is the provision of an improved means for removing the small valve sleeve and wire with the attached parts, if for any reason they are so stuck in the stem that the socket wrench cannot remove them, or if the wire is stuck in the stem so that it breaks away from its usual connection with the removable valve sleeve. This improved construction consists of a tapered threaded member, the point of which is small enough to enter the bore in the removable valve sleeve, left-hand threads being formed on the tapered end of this member so that by a left-hand turning movement, with the member entered in the valve sleeve, the member will tightly engage the removable sleeve and a turning movement in the direction to tighten it in the sleeve will turn the sleeve in a direction removing it from the inner threads of the valve stem. More than this, said tapered member is provided with a small groove in its threaded surface of a depth slightly less than the diameter of the wire of the valve core. This groove receives the wire of the valve core when the member is turned into engagement with the bore of the removable sleeve so that the wire is tightly clamped between the member and the sleeve by the operation of rotating the member in a left-hand direction to unscrew the sleeve from the valve stem. Thus when the sleeve is removed, the wire comes with it and also the parts connected with the wire, and in this manner the entire valve core may be positively removed even if the sleeve is tightly stuck in the valve stem or the parts of the valve core become separated from each other, as frequently occurs. Furthermore, as pointed

out, by making my improved device in sections threaded together, the complete device is of substantially the size of a tool handle, it is readily held in the hand of the operator for effective use, regardless of the particular part of the tool that is to be used, no projecting parts whatever are employed that can interfere with the turning movement of the tool in the hand of the user, and although the complete tool is no longer than an ordinary tool handle, no matter what part of the tool it is desired to use, one or more of the remaining parts or sections of the complete device are always available as part of the handle to effectively use the desired part of the tool, without in any way interfering with the turning of the tool in the hand of the user, affording the user at all times a positive hold or grip on the tool and without in any case presenting any sharp or rough end surfaces that might engage the hand of the user and injure it.

My invention will best be understood by reference to the accompanying drawings showing a preferred embodiment thereof in which—

Fig. 1 shows my complete device in side elevation;

Fig. 2 is a left-hand end view of the parts shown in Fig. 1;

Fig. 3 is a right-hand end view of the parts shown in Fig. 1;

Fig. 4 is a longitudinal sectional view of the parts shown in Fig. 1 in separated relation, the central one of the parts being shown partly in side elevation;

Fig. 5 is a longitudinal sectional view to an enlarged scale of the relation of the socket wrench portion of the tool when in use on a valve stem;

Fig. 6 shows in a view similar to Fig. 5 the wire and sleeve removing member in use on a valve; and

Fig. 7 is a sectional view of the sleeve removing member and parts engaged thereby during a sleeve removing operation, to a further enlarged scale, this view being taken along the line 7—7 in Fig. 6.

Similar numerals refer to similar parts throughout the several views.

As shown in Fig. 1, my device consists of three cylindrical parts 10, 11 and 12, each being nurled preferably on its outer surface to provide firm engagement with the fingers of the user, these parts having substantially the relation to each other indicated in Fig. 1 when they are screwed together.

As shown in Fig. 4, the portion 10 is provided with right-hand threads in its outer end as indicated at 10^a, these threads being of the same size and pitch as the threads on the outer surface of valve stems of the kind under consideration. The end of this threaded portion is provided with slots 10^b for receiving dirt and chips when the

threaded portion 10^a is screwed on a valve stem. The portion 10 may be made of tool steel and hardened, or the threads may be hardened in any other suitable manner so that they effectively operate as a cleaning die when screwed onto the external threads on the end of a valve stem intended to receive the valve cap. The other end of the part 10 is provided with similar threads 10^c for screwing the part 10 onto one end or the other as desired of the part 11, for which reason either the threads 10^a or the threads 10^c may be screwed onto either end of the part 11. The part 10 either may be made from solid stock and bored to receive the screw threads referred to, or it may if preferred be made from an iron or steel tube, the only preference being that the threads 10^a be hardened in one way or another so that they will stand up when repeatedly used as a cleaning die. It is further important that the part 10 be hollow so as to receive one or the other of the projecting axial members of the part 11.

The part 11 consists of a cylindrical rod 90 of iron or steel, which is preferably shorter than the part 10, this part being turned down at its ends and provided with external threads 11^a and 11^b of a size to fit the threads 10^a and 10^c so that these parts may be 95 screwed together in any relation desired. In one of the ends of the part 11, a member 13 is secured, this member consisting of a cylindrical rod, preferably of steel that may be hardened and having a tapered outer end provided with left-hand threads 14, the end of the tapered portion being of small enough diameter to readily enter the bore of a valve sleeve as indicated in Fig. 6. The threaded portion of the member 13 is provided with a 100 clearance groove 15 for a purpose to be described. The inner end of the member 13 is preferably slightly tapered so that said member may be tightly held in the part 11 in a corresponding bore, by forcing the member 13 tightly into the bore. A transverse hole 11^c is preferably formed in the part 11 in line with the inner end of the member 13 so that the member 13 may be removed from the part 11 by driving a wedge 115 into the hole 11^c against the end of the member 13. On account of the tapered construction of the inner end of the member 13, as soon as it is started outwardly from the position indicated in Fig. 4, it is loose in 120 the part 11 and may readily be removed so as to be replaced by a similar member, if for any reason it becomes damaged or worn. The other end of the part 11 carries an extending threaded portion 16 having right-hand tap threads on its outer surface, of a size and pitch corresponding with the internal threads of valve stems of the kind under consideration, thus adapting the part 16 to act as a cleaning tap for cleaning and 130

straightening the threads in the inside of a valve stem to facilitate removing the parts of the valve core or inserting a new core in an old valve stem. The tap 16 may be integral with the part 11 or may be inserted as desired, the only preference being that it shall be of iron or steel of such composition that it can be hardened in one way or another to insure that the tap threads will stand up under repeated use referred to.

The part 12 is provided in its outer end with a bore 12^a of slightly larger diameter than the outside diameter of the external threads of valve stems of the kind under consideration. Axially disposed in the bore 12^a, a wrench member 17 is provided, said member being either an integral part of the portion 12 or inserted therein as desired so that its outer end is substantially flush with the outer end of the part 12. The member 17 is of a diameter to clear the inner threads of valve stems of the kind under consideration, and this member is provided with a bore 17^a of a diameter to clear the wires of valve cores of the kind under consideration. The end of this member is provided with opposite slots or keyways 17^b, 17^c for engaging corresponding keys projecting from removable valve sleeves of the kind under consideration. It is desirable that the member 17 shall be of iron or steel that can be hardened in one way or another so that its slotted wrench portion may not be injured by repeated use. The other end of the part 12 is provided with a bore 12^b, the outer end of which is threaded as indicated at 12^c with threads of the same size and pitch as the threads 10^a and 10^c, the bore 12^b being of sufficient length to clear either the member 13 or the tap member 16 as desired, so that either end of the part 11 may be screwed into the part 12, if the use of the tool indicates that the part 12 should preferably be employed as a part of the handle when either end of the part 11 is in use to perform its intended purpose.

From the above description, it will appear that the only part of the device having projecting tool portions, is the part 11, and that the tool portions projecting from this part are in alignment with each other and project only axially from the part 11; it will also appear that the socket wrench construction described, besides providing a positive external guide, greatly facilitating the placing of the wrench in proper position in a valve stem, also serves as a shield for the wrench portion of the part 12, so that the wrench portion does not project beyond the end of the part 12, thus insuring that the wrench portion can do no injury to the hand of the user and can offer no annoyance to the user when the part 12 is used as a part of the handle in operating either of the tools carried by the part 11; also that when the parts

of the tool are screwed together, all of the tool parts are completely enclosed and protected so that they cannot be injured, for example by dropping the tool or hitting it accidentally with other objects.

70

It will further appear from the above description, that while either the part 10 or the part 12 may be used as a handle portion on either end of the part 11, when the tool is in its completely closed condition, the tool portion on either the part 10 or the part 12 is instantly available for use without any separation of the parts, and that but a single separation is required to use either of the tool portions carried by the part 11, the only operation required to use either of the tool portions of the part 11 being in effect the removing of a protecting cap, since the parts 10 and 12 serve as protecting caps for the tool portions carried by the part 11, but with the added advantage that each protecting cap also carries a tool portion for accomplishing one of the indicated purposes of the device.

75

In Fig. 5 I illustrate somewhat conventionally a valve stem and valve core of the kind under consideration. A valve stem is shown at 18 having external threads 18^a for receiving a closing cap and internal threads 18^b for receiving the removable sleeve 19 of the valve core. A valve wire 20 extends through the sleeve 19 to form a convenient means for loosening the valve member 21 if it becomes stuck for any reason, and for retaining the valve spring 22 in proper relation to the valve member 21 so that the inner parts of the valve construction constitute a complete assembly that may readily be inserted or removed from the stem 18 as a unit, assuming that the parts are not tightly stuck in the stem.

90

For any such latter condition, the socket wrench portion of my device may be employed as indicated in Fig. 5 to remove the sleeve 19 and associated parts, since under normal conditions the wire 20 is retained in the relation indicated by slight projections on its ends. In this operation of removing the valve parts or core, each of the projecting keys 19^a of the sleeve 19 is engaged by one of the slots 17^b of the wrench member 17, so that the sleeve may be unscrewed from the stem and a new core inserted in the same manner.

95

The relation of the parts indicated in Fig. 5 clearly illustrates the manner in which the end of the part 12 and the bore 12^a therein serve as a guide for centering the wrench portion 17 in the stem 18. In some cases however, the parts of the valve core become so stuck in the stem 18, that in attempting to remove the sleeve 19 by means of the wrench 17, the keys 19^a are sheared or broken from the sleeve 19, or under other conditions although the sleeve 19 may be unscrewed by the wrench 17, other parts of

100

105

110

115

120

125

130

the core are so stuck in the stem 18 that the outer projection formed on the wire 20 will not remove the inner parts of the valve core, with the result that the wire 20 and associate parts remain behind in the stem 18, making it extremely difficult to remove the wire 20 and remaining parts of the valve core. In such cases, the operation indicated in Fig. 6 is resorted to. As shown in this figure the member 13 is turned tightly into engagement with the bore of the removable sleeve 19, with the wire 20 in the groove 15 in said member. The effect of left-hand rotation of the member 13 is to screw the member 13 into the sleeve 19 in the same direction required to remove the sleeve 19 from the stem 18. This results in tightly clamping the wire 20 between the member 13 and the sleeve 19 as indicated in Fig. 7, and continued rotation in a left-hand direction serves to remove not only the sleeve 19, but also the wire 20 and the parts of the valve core attached thereto, after which the inner threads of the sleeve 18 may be cleaned by the tap member 16 and a new valve core may be inserted in the sleeve.

While I have shown my invention in the particular embodiment above described, it will be understood that I do not limit myself to this exact construction as I may employ equivalents known to the art at the time of the filing of this application without departing from the scope of the appended claims.

55 What I claim is:

1. In a valve tool, the combination of a plurality of cylindrical parts screwed together in axial alinement with each other and serving together to form a straight handle of convenient size to fit the hand of the user and wholly contained within the cylindrical boundary thereof, an intermediate one of said parts having threaded axial extensions comprising at one end a tap for cleaning the internal threads of a valve stem and at the other end of said part a tapered member provided with left-hand threads for removing a valve core from a valve stem, and the end ones of said parts each having at one end a bore for receiving one of said extensions in threaded engagement and provided at its other end with other valve repair devices contained within the cylindrical boundaries and lengths thereof of said end parts, said other valve repair devices comprising a die for cleaning the external threads of a valve stem and a socket wrench for removing a valve core from a valve stem.
- 60 2. In a valve tool, the combination of a plurality of cylindrical parts screwed together in axial alinement with each other and serving together to form a straight handle of convenient size to fit the hand of the user and wholly contained within the

cylindrical boundary thereof, an intermediate one of said parts having threaded axial extensions comprising at one end a tap for cleaning the internal threads of a valve stem and at the other end of said part a tapered member provided with left-hand threads for removing a valve core from a valve stem, and the end ones of said parts each having at one end a bore for receiving one of said extensions in threaded engagement and provided at its other end with other valve repair devices contained within the cylindrical boundaries and lengths thereof of said end parts. 70

75 3. In a valve tool, the combination of a plurality of cylindrical parts screwed together in axial alinement with each other and serving together to form a straight handle of convenient size to fit the hand of the user and wholly contained within the cylindrical boundary thereof, an intermediate one of said parts having threaded axial extensions comprising at one end a tap for cleaning the internal threads of a valve stem and at the other end of said part a tapered member provided with left-hand threads for removing a valve core from a valve stem, and the end ones of said parts each having at one end a bore for receiving one of said extensions in threaded engagement and provided at its other end with other valve repair devices contained within the cylindrical boundaries and lengths thereof of said end parts, 80

closed condition of said tool, the end of the part around said wrench forming a tubular guide therefor around the external threads of a valve stem when said wrench is in use.

5 6. In a valve tool of the class providing tool members, the combination of a tap for cleaning the internal threads of a valve stem, a die for cleaning the external threads of a valve stem and a wrench for removing 10 a valve core from a valve stem, a straight cylindrical handle consisting of a plurality of parts having end threaded engagement, one of said parts having said tap extending axially therefrom, and another of said parts 15 having a bore for receiving said tap and provided with said wrench, and a third one of said parts having at one end a die for cleaning the external threads of a valve stem, said tool members being wholly contained 20 within the cylindrical boundary of said handle for the closed condition of said tool.

7. In a valve tool of the class providing tool members, the combination of a tap for 25 cleaning the internal threads of a valve stem, a die for cleaning the external threads of a valve stem and a wrench for removing a valve core from a valve stem, a straight cylindrical handle consisting of a plurality of parts having end threaded engagement, said parts carrying said tool members on their ends, said tool members being wholly contained within the cylindrical boundary of said handle for the closed condition of said tool.

30 8. In a valve tool of the class providing tool members, the combination of a tap for cleaning the internal threads of a valve stem, a die for cleaning the external threads of a valve stem and a wrench for removing a valve core from a valve stem, a straight cylindrical handle consisting of a plurality of parts having end threaded engagement, said parts carrying said tool members on their ends, said tool members being wholly contained within the cylindrical boundary of said handle for the closed condition of said tool, one of said parts having extending therefrom a tapered member having left-hand threads for removing a valve core 35 from a valve stem and contained in another of said parts for the closed condition of said tool.

9. In a valve tool of the class providing tool members, the combination of a tap for 40 cleaning the internal threads of a valve stem, a die for cleaning the external threads of a valve stem and a wrench for removing a valve core from a valve stem, a straight cylindrical handle consisting of a plurality of parts having end threaded engagement, said parts carrying said tool members on their ends, said tool members being wholly contained within the cylindrical boundary of said handle for the closed condition of said tool, one of said parts having extend-

ing therefrom a tapered member having left-hand threads for removing a valve core from a valve stem and contained in another of said parts for the closed condition of said tool, said tapered member having a longitudinal groove in its threaded surface for receiving the wire of a valve core and clamping said wire between said member and the sleeve of the core during the removal of the latter from a valve stem. 75

10. In a valve tool of the class providing tool members, the combination of a tap for 80 cleaning the internal threads of a valve stem, a die for cleaning the external threads of a valve stem and a wrench for removing a valve core from a valve stem, a straight cylindrical handle consisting of a plurality of parts having end threaded engagement, said parts carrying said tool members on their ends, said tool members being wholly 85 contained within the cylindrical boundary of said handle for the closed condition of said tool, one of said parts having extending therefrom a tapered member having left-hand threads for removing a valve core 90 from a valve stem and contained in another of said parts for the closed condition of said tool, said tapered member having tapered engagement with the part carrying it and said latter part having a transverse opening through it adjacent the inner end of said tapered member to facilitate removing said tapered member from the part carrying it. 95

11. In a valve tool, a socket wrench for 100 removing a valve core from a valve stem comprising the combination of a supporting part, a tubular extension carried by said part and having a smooth bore loosely fitting over the external threads of a valve 105 stem, and a rod carried by said part in the bore of said tubular extension and coaxial therewith and of a diameter to enter a valve stem and clear the inner threads thereof, said rod having a bore to clear the wire 110 of a valve core and having alined slots extending diametrically across its outer end to engage the keys on the sleeve of a valve core, the outer ends of said tubular extension and said rod being substantially in the 115 same plane.

12. In a valve tool, a socket wrench for 120 removing a valve core from a valve stem comprising the combination of a supporting part, a tubular extension carried by said part and having a smooth bore loosely fitting over the external threads of a valve stem, a rod carried by said part in the bore 125 of said tubular extension and coaxial therewith and of a diameter to enter a valve stem and clear the inner threads thereof, said rod having a bore to clear the wire of a valve core and having alined slots extending diametrically across its outer end to engage the keys on the sleeve of a valve core, 130

the outer ends of said tubular extension and said rod being substantially in the same plane, a second supporting part, and a tapered member extending therefrom provided with left-hand threads for entering the sleeve of a valve core to remove the same from a valve stem, said first part having a

bore for receiving said member when not in use, said parts having threaded engagement with each other. 10

In witness whereof, I hereunto subscribe my name this 7th day of May, A. D., 1925.

EDWARD C. COOLEY.
